R. F. WILSON.

CARD CASE.

APPLICATION FILED DEC. 15, 1915.

1,223,013.

Patented Apr. 17, 1917.

UNITED STATES PATENT OFFICE.

ROLAND F. WILSON, OF DENVER, COLORADO.

CARD-CASE.

1,223,013.

Specification of Letters Patent. Patented Apr. 17, 1917.

Application filed December 15, 1915. Serial No. 66,988.

To all whom it may concern:

Be it known that I, ROLAND F. WILSON, a citizen of the United States, residing at Denver, in the county of Denver and State 5 of Colorado, have invented certain new and useful Improvements in Card-Cases, of which the following is a specification.

This invention relates to improvements in cases of the type used for holding packs of 10 playing cards, and its primary object resides in providing in connection with a case of novel construction, locking means to prevent the removal of its contents without detection.

15 It has frequently occurred that unscrupulous persons desiring to take unfair advantage of those with whom they play at cards, remove the pack of cards from its case, though the latter had been sealed in 20 the customary manner, and after having marked the cards, replace the pack and reseal the case so as to avert suspicion.

25 By the use of my invention, resealing of the card case without discovery, or removal of the pack from the case without breaking the seal is impossible, and players or purchasers are thus assured that a case having its seal in an unbroken condition, contains 30 a pack of cards in the identical condition in which it left the factory.

An embodiment of my invention has been shown in the accompanying drawings in the various views of which like parts are similarly designated, and in which,

35 Figure 1 is a perspective view of my improved card case in the locked condition,

Fig. 2, a longitudinal section through the case along the line 2—2, Fig. 1.

Fig. 3, a transverse section taken along 40 the line 3—3, Fig. 1,

Fig. 4, a development of the blank of which the card-case is constructed,

Fig. 5, a face view of the tabs at the end of the case showing a modified construction, 45 and Fig. 6 a sectional view of the upper end of the case with the flap 7 in the open position.

Referring to the drawings, my improved 50 card case is made of a single piece of card-board 2, cut and scored for folding as shown in Fig. 4 of the drawings.

The central section of the blank is divided

by parallel score lines 3 into a flap-member 7 and side members 8 and 9 which are separated from each other by the end members 55 10 and 11.

Two reinforcing members 12 extending laterally from one of the side members, are separated therefrom by edge members 13 which are formed between parallel score 60 lines 14.

The edge members have at one of their ends, flaps 4 which in practice are folded over the mouth of the case, and the end member 11 formed between the side members 8 and 9 of the middle section, has at its ends, tapering flaps 5 which are folded against the inner surface of the corresponding edge members to close the case at its 70 corners.

The flap 7 has a U-shaped incision to provide a tab 6 adjoining at a central point the score line which divides the flap from the adjoining end member 10.

The reinforcing members 12 have at their 75 extreme ends, similarly formed tabs 15, and the side member 9 has at its outer end a centrally disposed outwardly projecting tab 16.

The different tabs are apertured for the 80 application of a seal as will hereinafter be described.

The side member 9 has around the portion of its edge at which the tab 16 is connected therewith, a perforated or otherwise weakened line 17 which provides a tearing line to facilitate the separation of the tab from the case, and to provide at the same time a thumb opening which facilitates withdrawal of the flap 7 from the case after the seal is 90 broken.

The reinforcing members 12 have in their edges adjacent the tabs 15, incisions 18 which permit of the ready removal of the tabs 15 with the tab 16 when the latter is 95 separated from the member on which it is formed, along the tearing line 17.

To form the blank shown in Fig. 4, into the case illustrated in Fig. 1, it is folded at right angles along its several score lines, 100 whereby the two side members 8 and 9, the two end members 10 and 11, and the two edge members 13, are placed respectively, opposite to each other.

The flaps 5 on the end member 11 which connects the side members, are folded against the inner surface of the corresponding edge members.

5 The flaps 4 at the ends of the edge members are folded inwardly over the mouth of the case beneath the end-member 10 which connects the flap 7 thereto, and the reinforcing members 12 are folded upon the inner 10 surface of the side member 9 on which the tab 16 is formed.

When the parts are in this position, the tabs on the reinforcing member 12 and the side member 9, are in register and their 15 apertures present a continuous passage for the seal.

The different members of the case are secured in their relative positions by glue applied between the reinforcing members 12 20 and the side member 9 upon which they are folded, and between the three registering tabs 15 and 16.

After a pack of cards has been placed in the case, the flap 7 is tucked between the 25 pack and the side member of the case of which the connected tabs form part, thereby placing the edge member 10 over the mouth of the case, and bringing the tab 6 formed in the U-shaped incision of the flap 7, into 30 register with the connected tabs.

A rivet 16 of lead or other pliable material is passed through the alined apertures of the tabs and its headless end subjected to pressure to form a second head which fastens 35 the tabs together.

It will be seen from the above that by these means, opening of the case without discovery is effectively prevented, especially when one or both of the rivet heads bear 40 the impression of a die or stamp of peculiar design, as is indicated in Fig. 1 of the drawings.

To remove the cards from the case, the tabs are detached from the parts with which 45 they are connected, by tearing them conjointly along the weakened line 17 which not only detaches the seal by which the tabs were connected, from the case and permits of its being opened, but which also provides 50 a thumb-opening affording access to the flap 7 and facilitating its withdrawal from the case. This thumb-opening furthermore facilitates the removal of a pack of cards from the case.

55 In the form shown in Fig. 5, the tabs are provided with notches 20 to receive a band 21 forming part of a seal by which the tabs are connected.

Having thus described my invention what 60 I claim and desire to secure by Letters-Patent is:

1. A card-case comprising a body member having a tab and a weakened line along which to detach said tab, the said line being 65 formed to provide a thumb-opening in the

member when the tab is detached therefrom, a closing member having a tab registering with the first-mentioned tab, and a sealing device connecting said tabs for the connection of said members.

2. A card-case composed of a folded blank and including a side member and reinforcing members fastened together and having registering apertures, and a closing member having an aperture registering with the 75 other apertures, for the passage of a sealing device.

3. A card-case composed of a folded blank and including a side member and reinforcing members fastened together and having 80 registering apertured tabs extending outwardly in alinement with said side member, and a closing member having an apertured tab registering with the first-mentioned tabs for the passage of a sealing device.

4. A card-case composed of a folded blank including a side member having a tab and a weakened line along which to detach the same, said line being formed to provide a thumb-opening in the member when the tab 90 is detached therefrom, reinforcing members having tabs registering with the tab on said side-member, and a flap having a tab adapted to register with said registering tabs for their connection by a sealing-device.

5. A card case comprising a body member open at one end and having a tab in alinement with one of its sides, a lid connected at the other side of the body-member and having a folded flap adapted to be tucked between the contents of the case and the inner surface of the first-mentioned side, a tab extending from the folding line of the flap, to register with the first-mentioned tab, and a sealing device for the connection of the 105 tabs.

6. A card case comprising a body-member having an opening, a tab extending from an edge of said opening, a closing member folding along the opposite edge of said opening 110 to close the same, a flap on said closing-member, folded with relation thereto for insertion into said opening, a tab extending from the folding line of said flap to engage the first-mentioned tab when the closing 115 member is in its closed position, and sealing means for connecting said tabs.

7. A card-case composed of a folded blank and including a side-member and reinforcing members fastened together and having 120 registering tabs extending in alinement with said side-member, a closing member folding along another side member of the case, a flap on the closing member, folded with relation thereto to be inserted in the case, a tab extending from the folding line of said flap, in register with the first-mentioned tabs, and sealing-means for connecting said tabs.

8. A card-case composed of a folded blank and including a side-member and reinforc-

ing members fastened together and having
registering tabs extending in alinement with
said side-member, a closing-member folding
along another side-member of the case, a tab
5 extending from said closing-member, in reg-
ister with the first-mentioned tabs, and seal-
ing means for connecting said tabs.

In testimony whereof I have affixed my
signature in presence of two witnesses.

ROLAND F. WILSON.
